UNITED STATES PATENT OFFICE.

NATHAN C. STONER, OF SISTERSVILLE, WEST VIRGINIA.

PROCESS OF LINING WORKING BARRELS AND PIPES.

No. 816,890.

Specification of Letters Patent.

Patented April 3, 1906.

Application filed November 28, 1905. Serial No. 289,510.

To all whom it may concern:

Be it known that I, NATHAN C. STONER, a citizen of the United States of America, residing at Sistersville, in the county of Tyler and State of West Virginia, have invented certain new and useful Improvements in Processes of Lining Working Barrels and Pipes, of which the following is a specification, reference being had therein to the accompanying drawing.

This invention relates to a certain new and useful process of lining working barrels, pipes, valves, or the like; and the invention has for its primary object to provide a process of lining working barrels which can be expeditiously performed to insure a perfect lining of a working barrel or the like article.

To this end my process involves a plurality of steps, each of which is essential in properly lining a barrel. In this connection I line the working barrels or pipes with a strong and durable metal having a high tensile strength, such as brass; but in lieu of brass a non-corrosive material may be used. I am aware that working barrels and the like have been provided with vitreous linings, also with metallic linings; but mechanical means, such as collars and sleeves, have been employed to retain the linings within a working barrel. It is essential in lining a working barrel that said lining be practically air and water tight relative to the working barrel to prevent the lining from disintegrating by the chemical action which takes place between the lining and the different liquids or fluids in which it may be submerged. The use of working barrels in oil-wells, also the use of pipes within coal mines, is a fair example of the manner in which working barrels and pipes are affected by the liquids or fluids in which they are submerged. For instance, in the submerged pipes of coal-mines employed for pumping water from the mines it is a well-known fact that the submerged pipes are affected and disintegrated by the sulfur ingredients of the water within the mine. Consequently it is only a matter of time until the submerged pipe is rendered useless. This is also true of valves located upon pipe-lines leading from coal-mines, the sulfur ingredients of the water passing through the valves eventually rendering the valve-seats within the valves useless.

In my process of securing a lining within a

working barrel or pipe I employ positive and reliable means for effecting a perfect connection between the periphery of the lining and the inner sides of the working barrel or pipe, thereby preventing any fluid or liquid from percolating between the lining and the working barrel.

In order that the various steps of my improved process may be fully understood, I have illustrated in the accompanying drawing a form of apparatus or machine which I preferably employ, although I do not care to confine myself to the specific construction of the apparatus in carrying out the various steps of my improved process, it being obvious that other means than those illustrated can be readily employed for accomplishing the desired result.

In the accompanying drawing I have illustrated the apparatus by a side elevation, partly in section, and in describing my improved process the detail construction of the apparatus will be first considered and then the steps involved in lining the working barrel or pipe.

The apparatus consists of a supporting head or mandrel 1, which also serves functionally as a burner. The supporting-head comprises a cylindrical casing 2, having a countersunk central portion 3, which provides an annular groove 4. Centrally of the countersunk portion is formed a frusto-cone-shaped guide 5, having a vertically-disposed opening 6 formed therein, which communicates with a hollow standard 7, formed centrally of the cylindrical casing 2. The hollow standard serves to support a countersunk portion 3 of the cylindrical casing 2, and the bottom of the casing 2 adjacent to the standard 7 is formed with an inlet-port 8. Secured in the inlet-port 8 is a water-inlet pipe 9, carrying a regulating-valve 10 of a conventional form. The pipe 9 is provided with a drain-pipe 11, which is controlled by a conventional form of valve 12.

The top of the cylindrical casing 2 surrounding the annular groove 4 is provided with circumferentially - arranged apertures 14, and these apertures, in connection with the cylindrical casing 2, serve as a burner, the casing 2 being provided with a gas-inlet pipe 15, carrying a regulating-valve 16 and a mixer 17.

The casing 2, together with its appurte-

nant parts, may be suitably supported, and at a predetermined height above the casing 2 I provide a melting - pot 18. The melting-pot is supported by a bracket 19, pivotally mounted upon a standard or wall 20 of the compartment in which the apparatus is used. The melting-pot consists of a receptacle 21, which is heated by a conventional form of burner 22, said burner communicating with a suitable gas-supply pipe 23, regulated by a valve 24. The receptacle 21 is provided with an angularly-disposed spout or pipe 25, having a conventional form of regulating-valve 26, which is adapted to control the outlet of said receptacle.

Suitably supported above the melting-pot 18 is a water-pipe 27, the lower end of which is threaded, as at 28, in a head 29.

The different elements of my apparatus which I have just described embody the preferable form, and the various steps involved in lining a working barrel or pipe in connection with the apparatus will now be described.

The first step consists in properly positioning a working barrel or pipe 30 and a liner or lining-tube 31 upon the supporting head or mandrel 1. The "liner," as it will be herein-after termed, is first placed over the frusto-cone-shaped guide 5, the liner being supported in a vertical position within the annular groove 4 of the casing 2. The working barrel 30 is now placed over the liner, said working barrel resting in the annular groove 4 similar to the liner 31, but snugly fitting the vertical outer walls of the groove 4. The working barrel 30 is of a greater diameter than the liner 31, whereby a space will exist between the liner and the working barrel. The plug or head 29 is now placed in the upper end of the liner 31, thereby closing both ends of the liner.

The next step consists of placing a quantity of lead within the receptacle 21 and igniting the gas of the burner 22, the valve 26 being closed to prevent the lead after it has reached a molten state from flowing through the spout or pipe 25. The valve 16 is now opened to admit gas to the casing 2, and the gas is ignited at the apertures 14. The gas-flames travel upwardly over the periphery of the working barrel, gradually heating the same. The valve 10 of the water-supply pipe 9 is now opened to permit of the water passing upwardly through the hollow standard 7 and the guide 5 into the liner 31, it of course being understood that the valve 12 of the drain-pipe 11 has been closed. As the water fills the liner 31 it passes off through the outlet-pipe 27, thus providing a continuous circulation of the water within the liner 31, which tends to cool the same.

The next and most important step of my improved process consists of pouring the mol-

ten lead contained within the melting-pot 18 in the annular space which exists between the liner 31 and the working barrel 30. This is accomplished by shifting the melting-pot to a position adjacent to the working barrel, whereby the end of the spout or pipe 25 will be directly above the space between the liner 31 and the working barrel 30. The valve 26 of the spout or pipe is opened to permit of the space between the liner and the working barrel being filled with molten lead, at which time the valves 26 and 16 are closed and the working barrel permitted to cool. The water-supply passing through the pipe 9 is then closed and the valve 12 opened to drain the water contained within the liner 31. The head 29 is then removed from the liner 31 and the working barrel in its entirety removed from the supporting head or mandrel 1, at which time the operation just described can be continued with another working barrel and liner.

In the operation of securing a liner within a working barrel or pipe the molten metal tends to fuse and adhere to the working barrel, and as the liner is cooled from the interior and heated by the molten lead upon its periphery these two opposite temperatures contract and shrink the working barrel upon the liner, the liner being maintained in a normal condition by the cold water passing through the same. As the working barrel is cooled it contracts upon the liner, and, together with the molten lead which has been poured between the liner and the working barrel, forms an air-tight and water-tight connection.

It will thus be seen that by my improved process I am enabled to firmly secure a lining within a working barrel, and when the lining has been worn by constant use the working barrel can be heated to melt the lead, thus permitting of the worn liner being removed and the working barrel fitted with another lining. In some instances a brass liner will be employed, but in no wise do I care to confine myself to the material used in connection with the liner.

From the foregoing description it will be observed that working barrels and pipes can be expeditiously lined and that no mechanical means is used in connection with the working barrel to retain the liner therein other than the apparatus above described.

Summarizing the various steps of the process, the invention in its broadest aspect consists of using a binding or adhering element between the liner and the article to be lined, the element being interposed between the liner and the article in the heated state, whereby by artificially cooling the liner and the adhering element the article will shrink and contract upon the liner. In this manner various metallic and vitreous inner coverings

may be placed in working barrels or the like objects by subjecting the covering to a pressure caused by the contraction of the article, thus firmly uniting the two elements together with the binding or adhering substance.

5 What I claim, and desire to secure by Letters Patent, is—

1. A method of lining a working barrel comprising the mounting of a liner within a 10 barrel, heating the barrel, then artificially cooling the liner, then pouring a molten substance between the liner and the barrel, and allowing said substance and the barrel to cool whereby the contraction of the barrel and adhering element will cause said barrel to shrink 15 upon the liner, substantially as described.

2. The method of lining a barrel consisting of first placing a liner within the barrel, heating said barrel, pouring a molten adhering 20 substance between said liner and said barrel, and artificially cooling said liner to cause said barrel to shrink upon said liner, substantially as described.

25 3. The herein-described process of lining a barrel, consisting in interposing a molten adhering substance between said liner and said barrel, and artificially cooling said liner to cause said barrel to shrink thereon when the barrel cools, substantially as described.

30 4. The herein-described process of lining a working barrel, consisting in subjecting said

barrel to a high degree of heat, artificially cooling the liner within said barrel, and then pouring a molten adhering substance between said barrel and said liner, to cause said barrel 35 to contract upon said liner, substantially as described.

5. The method of uniting a liner to a working barrel, comprising the insertion of a heated 40 adhering substance between said liner and said barrel, and artificially cooling said liner, substantially as described.

6. The method of uniting a liner and a pipe 45 consisting in heating a pipe and simultaneously cooling a liner arranged within the pipe and then pouring a molten adhering substance between said liner, and said pipe, and then allowing the pipe to cool, to cause said pipe to shrink upon said liner.

7. A method of uniting a liner and a pipe 50 consisting in pouring a molten adhering substance between said liner and said pipe, and subjecting said substance to heated and cooled surfaces, to cause said barrel to adhere to said liner, substantially as described.

55 In testimony whereof I affix my signature in the presence of two witnesses.

NATHAN C. STONER.
